Attorney

UNITED STATES PATENT OFFICE.

ARTHUR A. WIRT, OF OMAHA, NEBRASKA.

WEEDING IMPLEMENT.

1,133,776.

Specification of Letters Patent. Patented Mar. 30, 1915.

Application filed January 22, 1914. Serial No. 813,692.

To all whom it may concern:

Be it known that I, ARTHUR A. WIRT, a citizen of the United States, residing at Omaha, in the county of Douglas and State of Nebraska, have invented certain new and useful Improvements in Weeding Implements, of which the following is a specification.

This invention relates to a weeding implement, and has for its object to provide a device consisting of few and simple parts so that manufacture thereof may be economical, and durability may be attained.

It also has reference to the mounting of certain metallic parts upon a handle in such a manner that the parts will remain firmly connected regardless of shrinkage or the stresses and strains incident to the use of the implement.

The invention consists of the novel construction, combination and arrangement of parts as described herein and claimed and as illustrated in the drawing, wherein,—

Figure 1 is a side view of the implement, the handle being broken away, a part of the collar and handle being in section. Fig. 2 shows a front view of the blade, the handle being broken away. Figs. 3 and 4 are side views of the implement. Fig. 5 is an end view of the implement. Fig. 6 is a side view of a part of the handle to clearly show the formation of a slot having an enlarged inner part or recess.

Referring now to the drawing for a more particular description, the implement consists, in part, of an elongated handle 7 having a slot 8 formed therein and longitudinally thereof to open upon one of its terminals, said slot having an enlarged inner part or recess 9; the handle is also provided with an aperture 10 disposed adjacent to and substantially at right angles to the slot.

I provide a metallic strip and bend it longitudinally between its ends to provide parallel adjacent portions *a* and *b* for a rectilinear tang having an enlarged terminal part or head 13 and providing a blade 11 and a hook 12. Since the enlarged part of the tang has a greater thickness than the combined thickness of portions *a* and *b* and is adapted to fill the enlarged part of the slot or recess 9, substantially, when disposed therein, it will be noted that this mounting provides such a construction that these parts will not become separated from the handle from effects of longitudinal stresses,

the slot being of such size that it is substantially filled by said portions *a* and *b*.

At 14 is indicated a sleeve or collar having a diameter normally corresponding to that of the handle, and after the head and portions *a* and *b*, by a movement transversely of the handle, have been inserted in the recess and slot, the collar may be moved outwardly to the end of the handle so that it will circumscribe the recess and slot and will provide a covering for the edges of the metal therein. The blade, preferably, is disposed parallel with the longitudinal axis of the handle and is provided at its free end with a convergent cutting-edge *c*. The hook is disposed at a suitable angle with reference to the blade, and its terminal is provided with a claw or outwardly curved teeth *d*.

At 15 is indicated a brace, its outer end being bent to traverse apertures *e* and *f* of the hook for a mounting thereon, its inner end being bent to provide a rectilinear portion *g* adapted to be disposed at right angles to the handle while disposed in aperture 10.

The brace, intermediate its ends, is bent outwardly to form a loop, buffer or head *h* for use so that the rectilinear part *g* may be driven through the aperture 10, as by use of a hammer or similar implement (not shown); and the brace near its inner terminal, preferably, is bent outwardly to provide a detent *k* to lie against the inner end and prevent a movement of the collar inwardly of the handle. A movement of the collar outwardly of the handle will be prevented by reason of engagement of the lug or inwardly curved part *m* of the brace with the projection or annular ridge *n* formed, preferably, upon and near its terminal. On account of shrinkage of the handle which may occur, this preferably being constructed of wood, it is desirable to provide such a mounting for the collar that a movement thereof, in either direction, longitudinally of the handle, will be prevented.

On account of the mounting for the collar as described, it will prevent a movement of the combined blade and hook, transversely of the handle, and a longitudinal movement of the blade and hook is prevented by reason of their mounting in the recess and slot, as explained.

The implement may be used to advantage for weeding gardens or flower beds, and is particularly useful for removing dandelions

from lawns. While the handle is supported inclinedly, in the position shown in Fig. 3, the blade may be easily thrust into the ground, and by twisting the handle slightly, 5 the soil will be loosened sufficiently so that, by use of the hook, while the implement is disposed in the position shown in Fig. 4, weeds may be quickly removed.

Having fully described my invention, 10 what I claim and desire to secure by Letters Patent is,—

1. In devices for the purpose described, an elongated handle provided at one of its ends with a recess having an enlarged inner 15 part, a metallic strip bent longitudinally between its ends to provide a rectilinear tang having an enlarged terminal part, a blade disposed substantially parallel with the tang and a hook disposed in angular 20 relation to the blade, said strip being adapted to be disposed with its tang engaging in said recess, the enlarged part of the tang engaging in the enlarged part of said recess, said blade being disposed substantially parallel 25 with the longitudinal axis of the handle, and a collar circumscribing the handle and providing a cover for the edges of the tang.

2. The combination of an elongated handle provided at one of its ends with a recess having an enlarged inner part, a metallic strip bent longitudinally between its ends to provide a rectilinear tang having an enlarged terminal part, a blade disposed substantially 30 parallel with the tang and a hook disposed in angular relation to the blade, said strip being adapted to be disposed with its tang engaging in said recess, the enlarged part of the tang engaging in the 35 enlarged part of the recess, the blade being disposed substantially parallel with the longitudinal axis of the handle, a collar circumscribing the handle, a brace engaging 40 the enlarged part of the recess, the blade being disposed substantially parallel with the longitudinal axis of the handle, a collar circumscribing the handle, a brace engaging

the hook and traversing the handle for preventing a movement of the collar inwardly 45 of said handle, and coacting devices upon the collar and brace for preventing a movement of said collar outwardly of the handle.

3. The combination of an elongated handle provided at one of its terminals with a recess having an enlarged inner part, a metallic strip bent longitudinally between its ends to provide a tang having an enlarged terminal part, a blade, and a hook disposed in angular relation to the blade, said strip 50 being adapted to be disposed with its tang and the enlarged part of the tang engaging, respectively, in the recess and in the enlarged part of said recess, and a collar mounted on the handle to overhang the 55 edges of the tang.

4. The combination of an elongated handle provided at one of its terminals with a recess having an enlarged inner part, a metallic strip bent longitudinally between its ends to provide a tang having an enlarged terminal part, a blade, and a hook disposed in angular relation to the blade, said strip being adapted to be disposed with its tang and the enlarged part of the tang engaging 60 respectively in the recess and in the enlarged part of said recess, a collar mounted on the handle to circumscribe the tang, a brace engaging the hook and traversing the handle for preventing a movement of the 65 collar inwardly of said handle, and coacting devices upon said collar and brace for preventing a movement of said collar outwardly of the handle.

In testimony whereof I have affixed my 70 signature in presence of two witnesses.

ARTHUR A. WIRT.
